UNITED STATES PATENT OFFICE.

GEORGE ALBEN E. LUNDELL, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed March 11, 1920. Serial No. 364,999.

To all whom it may concern:

Be it known that I, GEORGE ALBEN E.

LUNDELL, a citizen of the United States, residing at 960 Anderson Ave., New York, in 5 the county of Bronx and State of New York, have invented certain new and useful Improvements in Telephone-Exchange Systems, of which the following is a specification.

10 This invention relates to automatic and semi-automatic exchange systems, and more particularly to automatic selector switches in which electromagnetically controlled devices are employed, and is adapted for use 15 either as a selector or as a connector.

The principal object of this invention is to provide improved means whereby the activity of the brush sets of such switches is selectively controlled.

20 According to another object the activity of the brush sets is controlled by electromagnets equal in number to the number of differently characterized motions transmitted to the brush sets, without the necessity of providing additional electromagnets particularly for governing selection of 25 the brush sets.

A further object resides in the provision 30 of automatic selectors of substantial and rugged construction in which the stresses and strains set up during selection of the brush sets are carried by substantially straight and rigid parts to the rigid framework of the selector. In accordance with 35 this object, I provide such parts of simple and improved construction, and an efficient method of forming the same.

According to a further object, the selector 40 is inoperative if the movable member thereof becomes inadvertently displaced from its normal position, whereby incorrect selection due to such displacement is effectually prevented.

45 Another object relates to selecting the desired brush set by predetermining the extent of a preliminary reciprocal movement of the selector, and thus the necessity for a preliminary brush tripping zone is obviated and considerable space is saved, and 50 the margins in the selective mechanism may be adjusted or varied without increased height or space.

Other objects and advantages will appear

as the description of the invention progresses.

By means of this invention a switch is provided by which a large number of lines may be accurately and rapidly served, and whereby any line may be reached through one of a plurality of multiple connected 60 sets of brushes on a common shaft, each set having access to a particular group of lines only. For this purpose there is provided a panel board upon which a plurality of vertical rows of sets of stationary 65 terminals are mounted, each row being divided into sections, and each section having a set of cooperating normally inactive movable brushes individual thereto, all the corresponding brushes of the several sets 70 having access to the same row being connected in multiple. These rows of terminals may be multiplied horizontally across the panel to be accessible to as many individual switching mechanisms as may be necessary 75 to handle the greatest number of simultaneous calls. Each set of brushes is carried by a separate brush carrier mounted on a longitudinally movable brush shaft common 80 to the entire group of brush sets corresponding to a single row of stationary terminals.

In accordance with the present invention the terminals of any desired line are reached by first causing the set of brushes having access to the section containing the desired 85 line terminal to be released to engage the stationary terminals and then causing said set to traverse the terminals in the row until the terminals of the desired line are reached.

In the embodiment of the invention herein shown, all of the brush carriers are fixed to the brush shaft to move therewith. A set of brushes is secured to each brush carrier by means of laterally flexing spring arms. Certain of these arms have cam portions arranged to be engaged by rollers of insulating material at one end of a bell crank lever whereby the brushes are forced laterally to a position to pass by the stationary terminals without engagement therewith. One of these brush controlling levers is individual 100 to each brush set and is pivotally secured to the brush carrier immediately adjacent the brush supporting arms in such a manner that when the inwardly extending free arm 105 of the lever occupies a horizontal position,

the other end will project between the arms and the rollers of insulating material will engage the cam portions and will force the brushes to their retracted or inactive position. The brushes are maintained in their inactive position, except when a connection is being made or during a conversation, when one set of brushes, and only one is tripped.

10 A brush selecting or tripping device is provided which is adapted to engage the brush controlling lever of a desired brush set to release the brushes and allow them, upon movement of the brush shaft, to traverse the stationary terminals of their section while the other sets of brushes remain in their inoperative position but move with the shaft. This brush selecting mechanism comprises a plurality of U or J shaped members each pivotally secured along its straightened middle portion, equal in number to the number of brush sets, and each provided with a tension spring by which it may be retained in either of two resting positions. One of the upwardly extending arms of each tripping device is positioned so that in one of the resting positions it extends slightly to one side of the line of travel of the brush controlling lever of the brush set. The other upwardly extending arm is provided with a lug or flange adapted to be engaged by a projection secured to the movable brush rod and upon a relatively short movement of the brush shaft, to be moved by such engagement in a plane at an angle to the direction of movement of the rod, into its second resting position. In the latter position, the first mentioned arm intercepts the line of travel of the brush controlling lever of the brush set at a point slightly below the position of the lever after such short advancement. Thus it will be seen that after a relatively short movement of the brush shaft one upwardly extending arm is in line with the line of travel of the brush controlling lever of the brush set. The arm being somewhat shorter than the distance traversed by the brush set, upon movement of the shaft and brush sets in a reverse direction, the brush controlling lever of one brush set will collide therewith and will be rotated and the brushes, by reason of the resiliency of their supporting arms, will assume their operative position.

15 A second lug or flange is provided on the upwardly extending arm of the device, and is adapted to engage a projection secured to the movable brush rod in such a manner that by a relatively longer movement of the brush rod the arm will be moved by such engagement in a place at an angle to the direction of movement of the brush shaft, and into its original resting position, out of line with the line of travel of the brush controlling lever of the brush set.

The lugs or flanges of the several tripping devices are differently positioned relative to the normal position of the projections on the brush shaft, and selection of the brush set to be actuated is accomplished by controlling the extent of movement of the shaft before reversing the direction of motion, so as to determine the specially characterized tripping device which shall be left in its operative resting position.

75 In another form of the invention a form of tripping device is provided by which the rotation of brush controlling lever takes place during the upward movement of the brush shaft.

80 For a more detailed description of the invention, reference is now made to the accompanying drawings in which

Fig. 1 is a side elevation of a switch with parts broken away; Fig. 2 is a perspective view of one of the brush controlling levers; Fig. 3 is a sectional view on the line 3-3 of Fig. 1; Fig. 4 is an enlarged side elevation of one of the brush sets and the controlling device therefor; Fig. 5 is a perspective view of one of the tripping devices; Fig. 6 is a diagram of a telephone exchange system, showing so much thereof as is necessary to a full understanding of the invention; Fig. 7 is a side view of a modified form of tripping device; Fig. 8 is an end view of the operating arm of the tripping device of Fig. 7 taken on lines 8-8 of Fig. 7, before the same has been placed in its active position; Fig. 9 is a similar view after it has been placed in its active position; Fig. 10 is a view showing the blank from which one of the tripping devices of Fig. 5 is formed. Fig. 11 is a similar blank for use with a different set of brushes; and Fig. 12 indicates diagrammatically the respective positions of various parts of the mechanism at a certain stage in the operation.

105 The switch here disclosed is designed to serve a large number of lines, say up to five hundred and the terminals of such lines are divided into sections of one hundred lines each, and are duplicated on the opposite side of the board so as to be accessible to the brushes on each side thereof, as shown in Fig. 3. It is obvious, however, that the capacity of the switch may be varied by providing a greater or less number of sections, and a corresponding number of brushes, or by arranging more or less terminals in each section.

110 To avoid needless duplication of parts, and to more clearly illustrate the features of the present invention, only one selector switch is fully shown in Fig. 1.

115 Referring to the drawings, the frame of the selector mechanism of the present invention comprises the upright member 15, to which is rigidly secured the plates 16, 16, and the plate 59. The several banks of ter-

minals are fastened thereto in any suitable manner and are formed by electrically conducting strips of material 18, and alternate insulating strips 19 piled together in 5 several sections as shown in Fig. 1.

Each selector switch 646, see Fig. 6, co-acting with such terminals, comprises a longitudinal shaft 25 which carries a plurality of brush carriers 26, having a plate 35, se- 10 curely clamped to said shaft 25 by screws 27. Each brush set includes the brushes 31, 32, 33, 34, which are carried at the ends of the laterally flexible arms 36, 37, 38, 39 respect- 15 ively. These arms are rigidly secured at their other ends to the plate 35 of the brush carrier, and are insulated therefrom and from each other by plates of insulation. By their inherent resiliency these arms tend to force the brushes 31 and 32 toward the 20 brushes 33 and 34 and vice versa. Each of the arms 36 and 39 carries a block of insu- 25 lating material 41 by which the brushes of each pair are held in spaced relation, as shown in Fig. 3. Thus it will be seen that 30 although normally the brushes are held away from contact with any of the stationary terminals and thus are rendered in- 35 active, upon being tripped or released, the brush 31 will engage the terminal 42, the brushes 32 and 33 will engage the terminal 43 and the brush 34 will engage the terminal 44, and thus will become electrically active. Each of the brush arms is provided with a soldering lug 40, and the soldering 40 lug of the arms 37 and 38 are connected together electrically by means of a conductor (not shown).

The clamping plate 35 extends from the brush support 25, and is laterally offset ad- 45 jacent to said support, as shown in Fig. 3, and is provided with the face portion 46 and the rebent portion 47, as shown in Fig. 2. The brush controlling lever 48 is rotatably mounted between the main portion of 50 the clamping plate 35 and the rebent portion 47 on the pin 49.

The brush controlling lever 48 is in the shape of a bell crank, and is shown in its normal position in Fig. 2, and in this position the arms 50 thereof rest against the inner face of the portion 46 of the plate 35. Each of the arms 50 are provided with rollers 51 of insulating material on suitable pivotal pins, the ends of the pins being enlarged 55 so as to retain the rollers 51. The lever 48 also comprises the extension arm 52 disposed substantially central with respect to the face 46, for a purpose which will herein- 60 after appear and the resetting arm 53. The brush arms 37 and 38 are bent to form con- 65 verging cam members 54 and the substantially flat parallel portions 55. In the normal, inactive position of the brush set the rollers 51 engage the inner faces of these parallel portions and the brushes are thus

held in their retracted positions, in which they are free of their respective stationary terminals, as shown in Fig. 2.

The brush shaft 25, is hollow for the re- 70 ception of the circuit wires 56, 57, 58 which are drawn through suitable apertures ad- jacent to the brush supports. Branches from each of these wires are connected to the soldering lugs of the corresponding brush arms of the respective brush sets thus con- 75 necting the corresponding brushes of all the sets of the shaft in multiple. These cir- 80 circuit wires may be extended to the rest of the apparatus of the circuit, as shown in Fig. 6, in any suitable manner, as for ex- 85 ample, by means of flexible wires. Mounted between the uppermost plate 16 and the plate 59 is a commutator plate, shown in de- 90 tail in Fig. 6, contacting with which are the brushes such as 654 and 675, carried by the 95 brush rod 25.

Immediately opposite the respective brush sets the plates 16 are provided with upwardly extending ears 66, see Fig. 5. Loosely 100 mounted thereon by means of the pin 67 is 90 the U or J shaped tripping device 68. The ends of the pin 67 are flared or flattened to retain the pin in position.

The several trip fingers of a single selec- 105 tor switch are variously characterized, and differ from each other in respect to the length of the actuated end, so that each re- 110 sponds to a different degree of setting. They all are formed in the same manner, and the method of forming tripping devices in a 120 simple, efficient and improved manner will now be described. Such tripping devices are each formed from a blank of the form shown in Fig. 10, it being understood that the length of this blank may vary in accord- 125 ance with the particular type of completed tripping device which it is desired to form. One of the blanks for a differently char- 130 acterized device being shown in Fig. 11. Se- 135 lection is made of the blank, from a plurality of forms, according to the device which it is desired to obtain. Such blank has the two apertures 96 and the arm 70 is bent upwardly along the line 71, 72 to form an angle of substantially 90 degrees. The lug 73 is bent upwardly along the line 74, 75 to form an angle of substantially 90 degrees with respect to the portion 79. The lug 76 is bent upwardly along the line 77, 78 to form an angle of substantially 90 degrees with re- 140

spect to the portion 79. The shank 79 carry- 145 ing with it the extending lugs 73 and 76 is now bent upwardly through an angle of substantially 90 degrees, along the line 80, 81, so that the shank 79 is substantially par- 150 allel to the first bent arm terminating in the portion 70. The device may now be dipped in a solution to protect it from rust.

Secured to the shank 79 is the shoe or cam 155 85 having the substantially flat faces 86 and 160

88. This may be mounted on either face of the upwardly extending shank 79. On this cam presses the spring 89 the other end of said spring being fastened to the plate 16
5 in any suitable manner. When the tripping device 68 is rotated on its pivotal pin 67 to the right from the position illustrated in Fig. 5, the spring 89 rides on the extreme end of the flat faced portion 86 of the cam 85
10 and the tension of the spring 89 forces the tripping device back to its resting position as shown in Fig. 5. When the tripping device 68 is moved slightly towards the left of Fig. 5, the spring 89 rides over the hump 87 of the cam 85 and the tension of the spring 89 snaps the tripping device further to the left until the spring 89 rests upon the flat faced portion 88 of the cam 85, and thus the tripping device is caused to assume a second
15 resting position. The device is limited in its extreme motion by contact of the lower portion with the plate 16, and throughout its movement the spring 89 engages the cam 85. It will be seen that the tripping device
20 68 has two resting positions.

The brush support 25 is provided with a collar 90 for limiting the downward motion of the brush support in order that the circuit wires 56, 57 and 58 may not be injured or
25 grounded by contact with the plates 16 of the frame, and so that no part of the brush carriers interferes with the spring 89. Each brush carrier is provided with an integral
30 projection 91, which accordingly is longitudinally movable therewith.

The up driving electro-magnet 668 is provided, and upon actuation of this magnet, its armature forces the flattened portion 92 of the brush support 25 into intimate contact with the roller 93. The roller 93 is constantly driven in the direction indicated by the arrow, by any suitable source of mechanical energy. Thus when the magnet 668 is energized, and the manner of its energization in the operation of setting up a telephonic conversation will be subsequently set forth, the brush shaft 25 and the brushes carried thereby are driven in an upward direction, being retained in such displaced or off
35 normal position by means of a pawl 95 engaging teeth or slots (not shown) in the flattened portion 92. The down driving electro-magnet 698 is provided, and upon actuation of this magnet, its armature forces the flattened portion 92 of the brush support 25 into intimate contact with the roller 94. The roller 94 is constantly driven in the direction indicated by the arrow in any suitable manner. The actuation of the magnet 698 also
40 withdraws the pawl 95, and thus the brush support 25 and the brushes carried thereby are moved in downward direction.

The modification shown in Figs. 7, 8 and 9 may also be formed of substantially flat punched blanks, and differ from the type

above described in regard to the structure of the operating arm. Referring to Fig. 7, the arm 770 is bent upwardly and as shown in Figs. 8 and 9, is provided with the hook 702 and the cam portion 701. The lugs 776 and 773 are bent to an angle of substantially 90 degrees with respect to the shank 779 and the latter, carrying with it the respective lugs is bent so that the mean plane of the shank 779 is substantially parallel with the plane of the upwardly extending portion 770. This device is mounted on the pin 67 on the ears 66 immediately opposite the brush set with which it is adapted to operate, as will hereinafter be set forth. When the modification of my invention shown in Figs. 7, 8, and 9 is employed, the brush controlling levers 48 are mounted on the pin 49 in an inverted position, instead of as shown in Fig. 2. This arrangement brings the extension arms 52 and 53 into a position below the brush supporting flexible arms 36, 37, 38 and 39 and Fig. 3 may be read as being taken looking upwardly on the line 3—3 of Fig. 1, so far as it shows the parts of the brush set when used with the modification of Figs. 7, 8, and 9. Secured to the shank 779 is the shoe or cam 85 having substantially flat faces whereby the pressure of the spring 89 causes the tripping device to assume either of two resting positions. The device is limited in its extreme motion by contact of the edges of the horizontal portion with the plate 16. In the normal resting position of this tripping device the arm 770 is positioned to one side of the line of travel of the arm 52 of the brush support, as indicated in Fig. 8. In the operation of setting up a telephonic connection automatically, the brush support 25 is given a predetermined preliminary upward movement, by the actuation of the magnet 668, as will be more clearly described hereinafter. The several tripping devices associated with each selector switch are differently characterized, as regards the distance of the lugs 73 and 76 from the plate 16. Referring to Fig. 12, in which there is shown the preferred arrangement of the several types of tripping devices in schematic diagram, the tripping device of the lowermost brush set is relatively short, as compared with that of the second tripping device from the bottom of the figure, the distance between the lug 573 to the lower plate 16 being less than the distance from the lug 73 to the second plate 16. Upon advancing the brush support as stated, the several sets of brushes, together with the projections 91, thereof, are advanced. The lowermost projection, associated with brush set number one, soon collides with the lower surface of the lug 573, and as shown in the detail drawing in Figs. 5 and 7, this surface is at an angle to the vertical. Thus the lug 573 (cor-

responding to 73) acts as a cam, and the continued motion of the projection forces the tripping device to the left, as viewed in Figs. 12 and 5. Simultaneously or on still further movement of the brush support the projection 91 is brought into contactual relation with lug 576 and on account of the angular setting of this lug, the tripping device is pushed back into its normal resting position. Further movement of the brush support now causes the projection 91 of the second brush carrier to contact with and move the lug 73 of the tripping device associated with the second set of brushes, and the second tripping device is moved to the left, that is, to its second resting position, as viewed in Fig. 5. Let it be assumed that the register setting is such as now to deenergize magnet 668 so that the brush shaft is now brought to rest. The arm 770 of the lowermost brush has been returned to its normal resting position as shown in Fig. 8, out of the line of travel, indicated therein by the dotted line. The corresponding arms 25 of the tripping devices associated with brush sets number 3, 4 and 5 are also in the normal resting position of Fig. 8, the projection 91 not having reached the lugs 773 of such upper tripping devices, so that the arms 30 770 of such tripping devices are inactive.

To sum up, the tripping device of brush set 1 is normal, having been reset; that of brush sets 3, 4 and 5 are normal, not having been affected; so that only the tripping device of brush set 2 is in the second resting position. It will be readily understood that upon calling other wanted subscriber lines, either brush set 1, 3, 4 or 5 may be selectively placed in the second position, and in each of such cases only one tripping device, i. e., the one selected by determination of the extent of movement of the brush set. Such determination being under control of the register setting, as will be subsequently described in full.

In the circuit operation, the down magnet 698 is now energized. The attraction of the armature thereby withdraws the pawl 95 from the tooth or slot with which it has been engaged, the member 92 is pressed against the roller 94, and the brush shaft is thus moved downwardly.

It will be noted that upon approach of the brushes to normal arms 52 of brush sets 1, 3, 4, 5, that is of the non-selected brush set tripping devices, return along the dotted line of Fig. 8, to the position indicated. That of the selected brush set, in this example number 2, travels as shown in Fig. 9. The line of travel in these two figures remains unchanged of course, but the tripping device is in the off normal, active, resting position. Thus the arm 52 strikes the face of the portion 701 at an angle and moves the tripping device to the right as

indicated in Fig. 9. The spring 89 overrides the hump 87 of the cam 85 and tends to urge the tripping device to the right.

The latch portion 702 thus is brought into the line of travel of the arm 52.

The operation of the circuit, described later, deenergizes the down magnet 698; a preliminary reciprocal movement, during which the selective devices have been set has now been completed.

It will be seen that the margins of clearance between the several parts, concerned in the described selective operation may be materially widened as desired by merely modifying the various dimensions of the commutator plate 677 and of the blanks 79, etc., without sacrificing space or requiring a taller selector, since the selective movement is reciprocal whereby the distance traversed by the brush shaft during the brush selecting operation may be the same distance to be traversed subsequently in making terminal selection. This principle is broadly new and basic in the art.

The up magnet 668 is now energized, and the brush shaft is advanced upwardly. The outward end of arm 52 of the selected brush set, and no other, is held, and the advancement of its pivot pin 49 and carrier frame 35 causes the rotation of the brush controlling lever 48, it being remembered that in this modification the arms 52 and 53 are below the flexible arms, 36, 37, and 38. Thus the selected set of brushes is tripped.

The rollers 51 are thus extracted from the substantially flat portions 55 of the flexible arms 37, 38 and the pairs of arms 37, 38 and 39, 40 are permitted to approach each other. At the bottom of each bank of terminals there may be provided a guide for the brushes, to guide them into the rows formed by the terminals, and upward movement of the brush shaft brings the selected set of brushes, and those only, into electrical contact with the respective sets of terminals, under control of suitable relays and sequence switches, etc.

When release is desired, the down magnet 698 is energized, retracting the pawl 95 and pressing the member 92 into intimate contact with down roller 94. When the brush shaft returns to its home position the actuated brush set is returned to its normal inoperative position by the engagement of the lever 53, extending downwardly, with the upper face of frame member 16. This causes the insulating rollers 51 to engage the cam surfaces 54 on the arms 37, 38, thus forcing the brushes to their inactive position as shown in Fig. 3.

The arm 53 and the spring 89 are formed so that the arm 53 does not encounter the spring 89.

This modification provides a simple and efficient means of preventing positively the

inadvertent displacement of the tripping devices when the selector is at normal the arm 52 serving the double purpose of locking such trip devices (see Fig. 8) and coaxing 5 with rollers 51 to trip the selected brushes.

Returning now to the embodiment of the invention shown in Fig. 5, it will be recalled that the device 68 is adapted to take up either of two resting positions, and each 10 of the several tripping devices of this embodiment are differently characterized by being differently related to the pivot pins, and thus become actuated upon different degrees of movement of the projections 91.

Having advanced the brush shaft upwardly, as aforesaid, a desired one of such tripping devices is retained in its active position, in the same manner as mentioned for the modification; the upwardly extending 20 shank 79 of Fig. 5 being similar to the shank 779 of Fig. 7.

It is now to be understood that the brush controlling lever 48 is as shown in Fig. 2. Upon energizing the down drive magnet 25 698 the pawl 95 is retracted and the brush rod 25 returned to the home position, and the arm 52 collides with the end of the arm 70, said arm 70 intercepting the line of travel of the arm 52. Non-selected tripping devices have their respective arms 70 out of such line and consequently inactive.

The selected brush controlling lever is rotated, and the downward movement of the brush shaft causes the rotation of the brush 35 controlling lever and the withdrawal of the rollers 51 accordingly permits the brushes to assume their active position. They are then advanced to the wanted terminal.

When release is desired, the up magnet 40 668 is energized and the brushes are moved upwardly over the remaining terminals of the bank, (if any) and to the most fully advanced position which the shaft is capable of taking.

The upwardly extending arm 53 of the tripped set of brushes engages the lower face of the plate 16 next above the set of brushes and restores the insulating rollers 51, 51 to the substantially parallel portions 50 55, 55 and thus the brushes are reset into their normal, inactive position illustrated in Fig. 3.

Thus it is seen that all the terminals of the selected bank are wiped over once for 55 each connection established therein, and this wiping action is effective for cleaning the terminals at frequent intervals, and thus improves the reliability of the system.

The up magnet 698 is now deenergized in 60 a manner described below, and the down magnet 668 in turn actuated until the brush shaft is reset in its home position.

The operation of setting up a telephone connection will now be described.

Referring to Fig. 6, 601 represents a call-

ing subscriber's substation, and 602 represents a called subscriber's station. A called subscriber's station may be connected with the central office by means of line wires such as 603, 604 and upon removal of the receiver 70 at the station 601, these line wires may become connected through any suitable form of line finder or line switch (not shown) such devices being well known in the art to which this invention appertains, to a first 75 selector switch and sender. The circuit is thereupon closed from grounded battery 605, right hand winding of relay 606, conductor 604, substation 601, conductor 603, left hand winding of relay 606 to ground. 80

The consequent operation of relay 606 closes at its front contact a local circuit for the slow release relay 607. The calling subscriber now manipulates, in accordance with one digit of the desired number, the calling device 608, serially connected in the circuit of his substation, in the usual manner, opening the line intermittently and the impulses cause the intermittent release of relay 606 a corresponding number of times. Relay 607 90

because of its slow releasing characteristic does not release during these impulses and a circuit is closed once for each impulse caused by device as follows: ground, armature and back contact of relay 606, right 95 hand armature and front contact of relay 607, winding of slow release relay 609, switch arm 610, conductor 611, winding of stepping magnet 612, to grounded battery. Stepping magnet 612 is quick acting and re- 100

turns to each of the impulses by moving the ratchet wheel 613 in a clock-wise direction, and the arms 614, 615 in a similar direction. Thus the extent of movement of the ratchet wheel 613, and arms 614, 615 depends upon the number of impulses sent over the line. The relay 609 becomes actuated upon the initial closure of this circuit, and on account of its slow releasing characteristics remains operated during the 110

transmission of the entire set of impulses and accordingly closes at its front contact a circuit during this period for the stepping magnet 616; but upon cessation of the series of impulses the relay 609 releases and deenergizes in turn, the stepping magnet 616, the retraction of whose armature causes the rotation in a clockwise direction of the ratchet wheel 617 and the associated arms 610, 618, 619. The subscriber 115

now continues by again manipulating the calling device 608 and thereby transmits to the central office a similar set of impulses corresponding to the subsequent digit of the called subscriber's number. The relay 606 operates in the same manner as aforesaid, and controls intermittently a circuit from ground, armature and back contact of relay 606, armature and front contact of slow release relay 607, winding of slow release re- 120

lease relay 607, winding of slow release re- 125

lease relay 607, winding of slow release re- 130

lay 609, switch arm 610, conductor 620, winding of stepping magnet 621 to ground-
ed battery. The relay 609, remains in its
operated position during the transmission of
such impulses, as described for the previous
5 set of impulses, and closes a local circuit for
the magnet 616. The intermittent opera-
tion of magnet 621 causes rotation of the
ratchet wheel 622 and the associated switch
10 arms 623, 624, the extent of rotation being
determined by the number of impulses over
the line. The stepping magnet 612, ratchet
wheel 613, and the switch arms 614, 615,
15 comprise a so-called register switch for reg-
istering one of the digits of a called sub-
scriber's number and for convenience the
parts thereof are shown in the drawing be-
tween the dash dot line 625, 626 and the line
20 627, 628. Stepping magnets 621, ratchet
wheel 622 and switch arm 623, 624 comprise
a similar register switch for registering an-
other digit of the number and the parts
thereof are shown in the drawing between
25 the dash dot line 627, 628 and the line
629, 630. The stepping magnet 616, ratchet
wheel 617 and the switch arms 610, 618,
619 comprise a so-called steering switch for
successively connecting into operative re-
lation with the pulse relay 606 a plurality
30 of register switches and for convenience
the parts thereof are shown in the draw-
ing to the left of the dash dot line 625, 626.
It is understood that other forms of mecha-
nism may be employed in place of the par-
35 ticular forms of register switch and steer-
ing switch shown, without departing from
the spirit of the invention. There may be
substituted for example, in place of the reg-
ister switches, a bank of keys such as are
40 commonly employed in semi-automatic ex-
change systems and there may be substituted
for the steering switch a sequence switch or
similar structure, if desired. Furthermore
the number of register switches which may
45 be employed can be varied, and the manner
of the introduction to and withdrawal from
the system of such switches will readily oc-
cur to those skilled in the art to which this
invention pertains.
50 The power magnet 635, centering spring
636, and the several springs such as 627
shown to the left of the dash dot line 629,
630 in Fig. 6 comprise a rotary switch, com-
monly termed a sequence switch. The con-
55 struction of this switch includes a rotatable
shaft having a series of discs of fiber or
other insulating material secured thereto,
and adapted to be set into motion by the
energization of the power magnet. On
60 each side of each insulating disc is a circular
conducting plate which is cut away or skele-
tonized so as to provide any desired arrange-
ment of contacts. The plates on the oppo-
site sides of the discs are electrically united
65 by securing rivets. The rotatable discs are
represented in the drawing in each instance
by a double line. A plurality of contacts or
brushes is provided for engagement with
each pair of conducting discs and by means
70 of these and by properly cutting away and
arranging the plates on the insulating disc
they may be electrically connected to the
contacts at any stage or position of rotation
of the shaft. Such contacts are shown in
75 Fig. 6 as arrows or lines. The positions of
the sequence switch at which the various
contacts or brushes are in engagement with
the rotatable disc, are indicated by numerals
placed adjacent to the several contacts re-
80 spectively, with the exception of the center-
ing springs located immediately above the
power magnets, in which case the numerals
represent the positions in which the disc is
cut, and which therefore indicate the open
85 circuit positions of the disc. The sequence
switch springs shown to the right of the
dash dot line 629, 630 are operated by the
power magnet 635 in a manner similar to
those of the magnet 635. The brushes 639,
640, 642 indicate diagrammatically a selec-
90 tor switch of any suitable type, which may
be adjusted in a well known manner to
seize one of a group of trunks such as the
trunk consisting of conductors 643, 644, 645.
A description of a similar selector, and the
95 manner of operating it, will presently ap-
pear with reference to the selector 646.
Having adjusted the brushes 639, 640, 642
to contact with the terminals connected to
an idle trunk consisting of the conductors
100 643, 644, 645, a circuit is closed from ground,
switch arm 619, conductor 647, sequence
switch spring 648, power magnet switch 635
to grounded battery. The sequence switch
is moved under control of its centering
105 spring 636 out of position 1 and into posi-
tion 8.
A fundamental or selecting circuit is now
closed from grounded battery 649, left hand
winding of relay 650, sequence switch spring
110 651, conductor 652, conducting segment 673,
brush 654, conductor 655, sequence switch
spring 656, conductor 643, brush 639, se-
quence switch spring 657, right hand back
contact of the counting relay 0', winding
115 of the stepping relay 658, sequence switch
spring 659, brush 642, conductor 645, se-
quence switch spring 660 to ground. It will
be seen that when the selector is displaced,
inadvertently, and is held in such displaced
120 position by the pawl 95, this circuit cannot
be closed, since then brushes 675 and 654
would not contact with the segment 673.
Thus an efficient means of preventing in-
accurate selection due to starting from a po-
125 sition other than normal is provided.
The relay 650 operates and locks itself
over a circuit through the left hand front
contact and armature of this relay, con-
130 ductor 661, sequence switch spring 656, to

the conductor 643, independent of the circuit for initially energizing this relay which included the sequence switch spring 651. The operation for relay 650 also closed the following circuit; ground, right hand armature and front contact of this relay, sequence switch spring 662, conductor 663, power magnet 638 to grounded battery. Under control of the centering spring 634 the sequence switch is moved out of position 1 and into position 2. The relay 650 remains operative over the conductor 661 as aforesaid. The stepping relay 658 became operated in the fundamental circuit above described and closes a circuit by way of the sequence switch spring 665 and conductor 666 through the switch arm 615 to the pair of counting relays corresponding to the selection to be made, in accordance with the setting of the respective register switch. Let it be assumed that the switch arms 614 and 615 have been set by the subscriber's dialling operation above described into their fourth position. The conductor 666 is then connected to conductor 1 and the relay 1 is accordingly energized, closing at its front contact a locking circuit for itself to ground at sequence switch spring 667, independent of the initially energizing circuit just described. Relay 1' remains, however, short circuited. A circuit is closed from grounded battery through the up driving magnet 668, sequence switch spring 669, conductor 670, right hand front contact and armature of relay 650 to ground. The magnet 668 is energized and presses the rod 92 into engagement with the constantly driven roll 93 and the shaft 25 is advanced in an upward direction carrying with it the brushes, upwardly. The commutator brush 675 contacts with insulating and conducting segments of a commutator plate 676. Upon relatively slight advancement of the brush rod 25 the projection 91 shifts the flange 73 in a horizontal direction and the lever 68 is thus forced into its off normal resting position being held there by the pressure of the spring 89 against the flattened face of the shoe. The arm 70 now intercepts the line of travel of the controlling lever arm 52. The commutator brush 675 contacts with the lowerly disposed segment of the commutator bar 677 and establishes thereby a circuit from ground, sequence switch spring 678, conductor 679, commutator bar 677, commutator brush 675, conductor 655, sequence switch spring 656 and to the winding of relay 650, thereby establishing a short circuit for stepping relays 658. The consequent release of stepping relay 658 removes a short circuit from around the relay one prime and causes the actuation of the last mentioned relay. Relay 650 has remained operated, and continues the energization of magnet 668 and the advancement of the brush support. Commutator brush 675 now breaks its contact with the lowerly disposed segment of the commutator bar 677 and the short circuit from around stepping relay 658 is broken thus causing the actuation of relay 658. A circuit is now closed from ground, armature and front contact of relay 658, sequence switch spring 665, conductor 666, switch arm 615, conductor 1, armature and front contact of counting relay one prime, to the winding of the zero counting relay and to grounded battery. The winding of the zero prime counting relay is however short circuited. Upon continued advancement the projection 91 engages the flange 76 and shifts the lever 68 in a horizontal direction to restore the lever to its normal resting position in which the arm 70 of the lowermost tripping device is out of the line of movement of the control lever of the lowermost set of brushes. Simultaneously or upon still further advancement of the brush support brings the projection of the second set of brushes into engagement with the lug 73 of the second tripping device and moves the latter out of its normal inactive resting position and into its off normal, active resting position, it being held therein by means of the spring 89 as aforesaid. The commutator brush 675 contacts with the second segment of the commutator bar 677 and establishes thereby a circuit from ground, sequence switch spring 678, conductor 679, commutator bar 677, commutator brush 675, conductor 655, sequence switch spring 656 to the winding of relay 650 and thus establishes a short circuit for the stepping relay 658. The consequent release of stepping relay 658 removes the short circuit from around the 0' counting relay and causes the actuation of the last mentioned relay. The fundamental circuit is thus opened, and a circuit for power magnet 635, through sequence switch spring 637 is closed at the front contact of relay 0'. The sequence switch is moved under control of centering spring 636 into position 10. The counting relays release upon the opening of sequence switch spring 667. When the commutator brush leaves the second conducting segment of the commutator bar 677 the circuit for the relay 650 is broken and this relay retracts its armatures. The magnet 668 is deenergized, and the advancement of the brush support arrested. The brush support is retained in such advanced position by a pawl 95. A circuit is also closed from ground, right hand armature and back contact of relay 650, sequence switch spring 662, conductor 653, to the power magnet 638 and grounded battery for moving this sequence switch out

of position 2. Under control of centering spring 664 the sequence switch moves into position 3.

A circuit is now closed for down magnet 698 from ground, right hand armature and back contact of relay 650, sequence switch spring 674, magnet to battery, and the actuation of this magnet withdraws the pawl 95, presses rod 92 into intimate contact with the roll 94 constantly driven in the direction indicated by the arrow. The control lever arm 52 of the second set of brushes, and no other, collides with the upwardly extending arm 70 of the second tripping device since all other such arms are free of the line of movement of the respective brush set controlling levers: that of the first brush set having been displaced but reset, and those of the third, fourth and fifth brush sets having been left undisturbed in their normal inactive resting positions.

When the brush support reaches the normal position, and upon completion of the limited reciprocal motion just described, the fundamental circuit is again closed, as described above, and relays 650 and 658 are operated. The actuation of relay 650 opens the circuit of down drive magnet thus discontinuing the further movement of the brush support in a downward direction.

It will be seen that the construction of the arm 79 of the lever 68 is different in the several cases for the various brush sets, in that the lugs 73, 76 are variably positioned on their respective arms. The arms 70 which intercept the line of travel of the controlling lever arms 52 of the brush sets may be equal or variable in length as desired. I have shown in the present embodiment these arms 70 as being substantially equal in the several cases. It will also be seen that these arms transmit the stresses and strains set up by the engagement of the controlling lever with the tripping lever are carried through to the frame work of the selector switch in a simple and direct manner, and the parts are of simple and rugged construction, and the entire construction is such as to insure long life to the mechanism.

The operation of relay 658 now establishes a circuit for the counting relay to which the arm 624 is connected, this being dependent upon the extent of movement of the register switch by the calling subscriber. Assuming that four impulses had been sent in by the subscriber in setting this register, the arm 624 is connected to the armature of counting relay 3' and a circuit is thereby closed for the operation of counting relay 3, causing the actuation of this relay. The operation of relay 650 closes the following circuit; ground, right hand armature and front contact of relay 650, sequence switch spring 662, conductor 653, power magnet 638 to ground battery, moving the sequence switch out

of position 3 and into position 5. A circuit is now established for the driving magnet 668 as follows: grounded battery, magnet 668, sequence switch spring 669, conductor 670, right hand contact and armature of relay 650 to ground. The brush support is pressed by the actuation of the magnet 668 into intimate contact with the roller 93, and the brushes are thus again moved upwardly. During such second upward movement a circuit becomes intermittently closed from ground, sequence switch spring 678, commutator segment 680, commutator brush 654, conductor 655, sequence switch spring 656, to short circuit the stepping relay 658 intermittently. The counting relays are actuated in turn, beginning with the 3' counting relay, until a sufficient number of impulses have been transmitted over the line to cause the operation of the 0' counting relay. The energization of the 0' relay opens the fundamental circuit for arresting the upward travel of the selector 646; and closes a circuit, ground, left hand armature and front contact of 0' relay, sequence switch spring 637, power magnet 635 to grounded battery for moving the sequence switch out of position 10—and the centering spring 636 carries it to position 16. The counting relays release upon the opening of sequence switch spring 667. The opening of the fundamental circuit arrests the travel of selector 646 in the same manner as before, the release of relay 650 breaking the circuit of magnet 668. A circuit is closed, ground, right hand armature and back contact of relay 650 for moving the sequence switch out of position 5 and into position 7. A circuit is now closed from ground, sequence switch spring 681, right hand winding of relay 650, for operating this relay, and another ground, right hand armature and front contact of this relay, sequence switch spring 662, to power magnet 638 for moving the sequence switch out of position 7 and into position 8. The relay 650 remains actuated while the brushes 32, 33 contact with busy lines, since busy lines have a guarding ground connected with the third wire of such lines. The circuit for retaining the relay 650 in its operated position during the test of busy lines is as follows: ground, conductor 682, brushes 32, 33 in multiple, conductor 683, sequence switch spring 684, conductor 661, left hand armature and front contact and winding of relay 650, to grounded battery. A circuit is therefore closed as follows: grounded battery, driving magnet 668, sequence switch spring 669, conductor 670, right hand front contact and armature of relay 650, to ground for actuating the driving magnet 668. The brushes are thereby advanced until the terminals of an idle line are found, and until the brushes 31, 32, 33, 34 are properly cen-

tered thereon, this centering being controlled by the centering segments of the commutator bar 685. Having reached the terminals of an idle line, relay 650 retracts 5 its armature, there being no guarding ground on the test terminal of such a line, and deenergizes the magnet 668. A circuit is now closed from ground, sequence switch spring 660, left hand back contact and armature of relay 650, conductor 661, sequence switch spring 684, conductor 683, brushes 32, 33 in multiple, test terminal of the line, winding of cut off relay 686, to grounded battery, for preventing seizure by others 15 of this line, and for operating the cut off relay 686.

A circuit is closed from ground, righthand armature and back contact of relay 650, sequence switch spring 662, conductor 653, 20 power magnet 638 to grounded battery, for moving the sequence switch out of position 8, and the centering spring 664 carries the sequence switch into position 14. Any suitable form of ringing control may be employed, that shown comprising the ringing current source 687, the tripping relay 688, which in combination with the sequence switch, impress a calling current on the called subscriber's line for operating the bell 30 at the called station. The response of the called subscriber, who removes his receiver, so increases the current in the winding of relay 688 as to cause its operation, and the sequence switch is moved out of position 14 35 by virtue of a circuit through the front contact of relay 688 and sequence switch spring 689. In position 16 conversational current is supplied to the called subscriber's talking apparatus over the following circuit, ground, 40 right hand winding of relay 690, sequence switch spring 657, brush 639, conductor 643, sequence switch spring 656, brush 31, the line wires and substation of the called subscriber, brush 34, sequence switch spring 691, conductor 645, brush 642, sequence switch spring 659, left hand winding of relay 690 to grounded battery. Relay 690 operates. The lines of the calling and called subscribers are now conversationally joined through the condensers 692, 692.

Upon completion of conversation, the respective subscribers replace their receivers, thus releasing relays 606 and 690, and releasing in turn the slow release relay 607, and 55 closing the following circuits: ground, armature and back contact of relay 606, armature and back contact of relay 607, sequence switch spring 648 to power magnet 635, for moving the sequence switch out of position 60 16 and into position 17. A circuit is now closed from ground, sequence switch spring 672, switch arm 618, back contact of stepping magnet 616, winding of this magnet, to grounded battery, and under control of its 65 self interrupted contact, the steering switch

is moved through the various off normal positions until the arm 618 breaks the circuits to the contacts and winding of magnet 616. The arms 610, 611 and 618 are now in the normal position shown in Fig. 6 in a manner well known in the art. A circuit is now closed for operating magnet 612 in the same manner, this circuit comprising the arm 618 at normal and arm 614 off normal, and the self interrupted contacts of the magnet 612, 70 the consequent intermittent operation of the magnet 612 bringing the arms 614 and 615 to normal. A circuit thereupon becomes closed by way of arms 618 and 614, both at normal and arm 623 off normal, the self interrupted 75 contacts and winding of magnet 621, and the arms 623 and 624 are brought to normal in the same manner. A circuit is now closed from ground, sequence switch spring 672, 80 switch arms 618, 614 and 623, all at normal, conductor 671, power magnet 635 to grounded battery, for moving this sequence switch out of position 17 and into position 1, its normal position. In passing through position 85 18 of this sequence switch the brushes 639, 640, 641, 642 are restored to normal in a well known manner.

The movement of the sequence switch out of position 16 as aforesaid, breaks at the 90 spring 634 the circuit of relay 633 which accordingly retracts its armature. A circuit is now closed from ground, armature and back contact of this relay, sequence switch spring 689, conductor 653, power magnet 638 for moving the associated sequence switch out of 95 positions 15, 16 and into position 17.

A circuit now becomes closed, according to one embodiment of my invention, from ground, sequence switch spring 669, driving magnet 668 to grounded battery, for actuating the magnet, and the brushes are advanced to their fully advanced position at the top of the terminal bank. The restoring lever 53 at the tripped brush set collides with the lower face of the bearing plate 16 and the controlling means 48 are rotated to position the insulating rollers 51 between the pairs of resilient brush supporting arms, and the brush set is thus caused to resume its normal 100 inactive position. A circuit is now closed from ground, sequence switch spring 692, 105 commutator brush 654, segment 693 closed only at the upper portion of the commutator plate 676, sequence switch spring 694, power magnet 638 to grounded battery, for moving the sequence switch out of position 17 and into 110 18, and the magnet 668 is deenergized.

A circuit is now closed from ground, right hand armature and back contact of relay 650, sequence switch spring 674, down drive 115 magnet to grounded battery, and the actuation of this magnet withdraws the pawl 95 and presses the rod 92 into intimate contact with the roller 94, constantly driven in the direction indicated by the arrow. The 120

brushes are thus driven in a downward direction, and when commutator brush 675 contacts with the normal segment 673, a circuit is closed, ground, sequence switch 5 spring 692, conductor 655, commutator brush 675, segment 673, conductor 652, sequence switch spring 651, power magnet 638 to grounded battery, for moving the sequence switch into its normal position 18, and the magnet 698 is deenergized.

The apparatus is now restored to normal, and ready for a subsequent call.

In case all lines of a sub-group are busy, the selector 646 is advanced to the end of the 15 group, and commutator segment closes a circuit, ground, sequence switch spring 692, conductor 655, commutator brush 675, commutator segment 696 (closed at the end of a sub-group), sequence switch spring 694, 20 power magnet 638 for moving the sequence switch into position 16, in which a distinctive tone may be given the calling subscriber through the sequence switch spring 697; and when the calling subscriber replaces his receiver, the apparatus returns to normal in 25 the same manner as for the regular call previously described.

The operation of the modification of Figs. 7, 8 and 9 is similar to the above, and the 30 description of the exchange apparatus can be read with it; it being only necessary to consider Fig. 2 as having the brush controlling lever 48 inverted, and Fig. 3, so far as it shows the brush structure as being taken 35 on line 13—13 of Fig. 1; also the numerals of Figs. 7, 8, and 9 are substituted for those of the structure of 5 and to facilitate this the tens and units digits of the reference characters for like parts are the same.

40 With the modification of Figs. 7, 8, and 9 the second upward movement of the brushes may be, if desired, omitted, and if so, the sequence switch may be readily modified by omitting position 17 as a stopping position 45 by omitting the centering spring 664 opening in position 17. The paragraph above beginning "A circuit now becomes closed" is then understood to be omitted.

50 Thus it will be seen that the tripping of a desired set of brushes has been accomplished by the use of switch operating magnets no more in number than the number of characters of motions; that is, one for the up motion, one for the down motion, and no 55 more. Furthermore, the tripping devices of the respective brush sets are individual and require no interconnection, and thus may be readily carried in stock, are easily transportable and replaceable.

60 Other arrangements, forms and positions, according to which the present invention may be practiced, will readily occur to those skilled in the art to which it pertains. The broad aspect of my invention is that selection 65 of a desired brush set is accomplished by

return of the shaft, so as to conserve space and improve the margins of manufacture, and I have preferred to show this inventive idea in combination with a particular form of switch, in itself an improvement; but it 70 is understood that the scope of the invention is not to be determined by this disclosure but that reference is to be made to the appended claims for that purpose.

What is claimed is:

1. In an automatic switch, a plurality of rows of terminals, a plurality of sets of brushes engageable therewith, resilient supporting means for said brushes, a shaft for moving said brushes, brush-controlling means for laterally flexing said supporting means whereby said brushes are caused to occupy an inoperative position between said terminal rows, and a tripping device operated by said shaft whereby said brush sets 80 may be selectively released.

2. In an automatic switch, a plurality of rows of terminals, a plurality of sets of movable brushes engageable therewith, resilient supporting means for said brushes, a shaft for moving said brushes, brush-controlling means for laterally flexing said supporting means whereby said brushes are caused to occupy an inoperative position between said terminal rows, and a plurality of 90 variously positioned tripping devices operated by said shaft whereby said brush sets 95 may be selectively released.

3. In an automatic switch, a shaft, a row 100 of stationary terminals divided into a plurality of sections, a corresponding plurality of sets of brushes resiliently secured to said shaft, a controlling means individual to each set for normally retaining said brushes in inoperative position, a trip lever operated by said shaft to effect engagement with one of said controlling means whereby a predetermined brush set may be rendered active and means for moving said shaft longitudinally to cause the selected brush set to traverse the stationary terminals in its respective section.

4. In an automatic switch, a brush shaft, a plurality of sets of brushes resiliently secured thereto, means for causing a plurality of stages of longitudinal movement of said shaft, controlling levers, one for each set, whereby the brushes thereof are normally maintained inactive, a plurality of trip fingers, one for each lever, but normally out of line of movement thereof, and means operated by said shaft whereby said fingers may be moved during the preliminary movement of said shaft to intercept the line of travel of the controlling levers of said brush sets.

5. In an automatic switch, a brush shaft, a plurality of sets of brushes resiliently secured thereto, means for causing a plurality of stages of longitudinal movement of

5 said shaft, controlling levers, one for each set, whereby the brushes thereof are normally maintained inactive, a plurality of variously characterized trip fingers, one for each lever, but normally out of the line of movement thereof, and means operated by said shaft whereby said fingers may be moved during the preliminary movement of said shaft to intercept the line of travel of 10 the controlling levers of said brush sets.

6. In a switch, a longitudinally movable shaft, a plurality of brushes resiliently secured thereto, means for normally retaining said brushes in inactive position, an electro- 15 magnet for advancing said shaft, a second magnet for restoring said shaft, and means operative during said restoration for selectively actuating said retaining means to release a desired brush into active position.

20 7. In a switch, a shaft, an electromagnet for advancing said shaft, a second electromagnet for moving said shaft in a different direction, group selecting means comprising means for rendering said selecting means active upon relatively short advancement of said shaft, means for rendering said selecting means inactive upon further advancement of said shaft, and means for actuating said selecting means upon movement of said 25 shaft in said different direction.

8. In an automatic switch, a shaft, a plurality of sets of brushes resiliently secured thereto, means for causing a preliminary reciprocal movement of said shaft, a corresponding plurality of normally inactive trip fingers constructed to render operative the respective sets of brushes, and means operated by said shaft during the reciprocal movement of said shaft rendering said 35 fingers active.

40 9. In an automatic switch, a brush shaft, a plurality of brushes resiliently secured thereto, means for causing a preliminary reciprocal movement of said shaft, controlling levers, one for each set, whereby the brushes thereof are normally maintained inactive, a plurality of variously characterized trip fingers, one for each lever, but normally out of the line of movement thereof, 45 and means operated by said shaft whereby said fingers may be moved during the reciprocal movement of said shaft to intercept the line of travel of the controlling levers of said brush sets.

50 10. In a selector switch, a support, a plurality of sets of brushes secured thereto, means for advancing said sets of brushes, selective means whereby a selected set of brushes may be rendered active according to the degree of advancement, and means for restoring said brushes to normal upon advancement thereof to the fully advanced position of said sets of brushes.

55 11. In a selector switch, a support, a plurality of sets of brushes secured thereto,

means for advancing said sets of brushes, selective means whereby a selected set of brushes may be rendered active according to the degree of advancement, and means operative in the fully advanced position 70 of said support for restoring said brushes to normal.

12. In a switch, a support, a plurality of sets of brushes resiliently secured thereto, a movable lever, means for maintaining said lever in either of two resting positions, and a stud secured to said support adapted upon movement of said support to shift said lever from one resting position to the other and controlling means normally separating the brushes of each set from each other to render the set inoperative, said controlling means positioned to engage said lever in a single one of its positions.

13. In a switch, a plurality of sets of brushes, means for maintaining said sets of brushes normally inactive, a lever for actuating said maintaining means, means for forwardly moving said brushes, driving means for moving said brushes in a reverse 85 direction, and means operative upon said forward movement for rendering said lever active, said maintaining means adapted to free a desired set of brushes upon said reverse movement.

14. In a switch, a movable shaft, a plurality of brushes secured thereto, selective means for rendering said brushes active, means operated by relatively short advancement of said shaft for rendering said selective means active, means operated by additional advancement of said shaft for rendering said selective means inactive, and means operated by restoration of said shaft to normal for rendering said selective means 105 inactive.

15. In a selector switch, a support, a plurality of sets of brushes resiliently secured thereto, driving gear for moving said support and brushes, a controlling lever normally maintaining said brushes in inactive position, a trip lever having two resting positions adjusted in one of said positions to intercept the path of movement of said controlling lever and in the other of said positions to clear the path of movement of said controlling lever, a stud secured to said support positioned to shift said lever from one position to the other upon relatively short movement of said support and to restore said lever to its original position upon relatively greater movement of said support.

16. In a switch, a longitudinal shaft, a plurality of sets of brushes resiliently secured thereto, controlling levers, one for each set, whereby the brushes thereof are normally maintained inactive, a plurality of variously characterized trip fingers, one for each lever, a corresponding plurality 125 130

- of spring pressed cams for maintaining said fingers in either of two resting positions, a corresponding plurality of studs secured to said shaft adapted upon varying degrees 5 of movement thereof to shift said fingers sequentially from one position to the other, said fingers positioned in one position to be out of the line of movement of said controlling levers and in the other position 10 to intercept the line of movement of said levers, means for causing a preliminary reciprocal movement of said shaft for setting said levers, and means for controlling the extent of said movement to predetermine the 15 finger to be selectively positioned in its second resting position.
17. In a selector switch, a plurality of sets of brushes, tripping means for selectively tripping desired sets of brushes constructed to be positively locked, if unselected, during the tripping operation.
18. In a selector switch, a plurality of sets of brushes, tripping devices for tripping desired sets of brushes, a single means for locking each of said tripping devices when unselected and for rendering the respective set of brushes active when selected.
19. The combination with a selector switch having movable and stationary terminals arranged in groups, of a sequence switch, means to position said sequence switch to control the movement of said movable terminals over all the stationary terminals of a group upon each selection of 35 said group irrespective of the electrical condition of the terminals in said group.
20. The combination with a selector switch having stationary and reciprocally movable terminals arranged in groups, of a sequence switch, means to position said sequence switch to control the reciprocal movement of said movable terminals upon selection of a group.
21. In a switch, a longitudinally movable shaft, a plurality of sets of brushes resiliently secured thereto, means for normally retaining said brushes in inoperative position, means for advancing said shaft a predetermined distance, means for returning 45 said shaft a corresponding distance, and a tripping device whereby said sets of brushes may be selectively tripped during such return.
22. In a switch, a longitudinally movable shaft, resilient arms uniting said brushes to said shaft, means for laterally displacing the brushes of each set whereby said brushes are rendered inoperative, means for advancing said shaft a predetermined distance, means for retracting said shaft, and a tripping device whereby said brushes may be selectively released during such retraction.
23. In a switch, a support, a plurality of sets of brushes resiliently secured thereto, controlling means normally separating the 50 brushes from each other to render the set inoperative, means for selectively advancing said support, means for returning said support, and a tripping device for selectively actuating by such return said controlling means to release a desired set of brushes.
24. In a switch, an axially movable support, a plurality of sets of brushes secured thereto, a controlling means for each set normally holding the brushes thereof spaced to inoperative position, means for forwardly setting said support, means for retracting said support, and a tripping device whereby any desired brush set may be rendered active during such retraction.
25. In an automatic switch, a longitudinally movable shaft, a plurality of brush sets fixed to said shafts, controlling levers for said sets, respectively, normally holding 55 said brushes in their inoperative position, a tripping device having a plurality of fingers positioned at progressively increasing distances from the normal position of said levers, and means whereby said tripping device may be displaced during the return of said shaft to effect operative engagement of a portion of said tripping device with the controlling lever of a predetermined brush set.
26. In a telephone exchange system, lines, a selector for seizing a line, said selector comprising a support, a plurality of sets of brushes resiliently secured thereto, a movable lever, means for maintaining said lever in either of two resting positions, and a stud secured to said support adapted upon movement of said support to shift said lever from one resting position to the other, and controlling means normally separating the 60 brushes of each set from each other to render the set inoperative, said controlling means positioned to engage said lever in a single one of its positions.
27. In a telephone exchange system, lines, 100 a selector for seizing a line, said selector comprising a movable shaft, a plurality of brushes secured thereto, selective means for rendering said brushes active, means operated by relatively short advancement of said shaft for rendering said selecting means active, means operated by additional movement of said shaft for rendering said selective means inactive, and means operated by restoration of said shaft for rendering said selective means inactive.
28. In a telephone exchange system, lines, 110 a selector for seizing a line, said selector comprising a longitudinal shaft, a plurality of sets of brushes resiliently secured thereto, controlling levers, one for each set, whereby the brushes thereof are normally maintained inactive, a plurality of variously characterized trip fingers, one for each lever, a corresponding plurality of spring pressed cams 115
- 120
- 125
- 130

for maintaining said fingers in either of two resting positions, a corresponding plurality of studs secured to said shaft adapted upon varying degrees of movement thereof to shift said fingers sequentially from one position to the other, said fingers positioned in one position to be out of the line of movement of said controlling levers and in the other position to intercept the line of movement of said levers, means for causing a preliminary reciprocal movement of said shaft for setting said lever, and means for controlling the extent of said movement to predetermine the finger to be selectively positioned in its second resting position.

29. In a telephone exchange system, subscribers' lines, a selector for seizing a line, said selector comprising a longitudinally movable shaft, a plurality of sets of brushes resiliently secured thereto, means for normally retaining said brushes in inoperative position, means for advancing said shaft a predetermined distance, means for returning said shaft a corresponding distance, and a tripping device whereby said sets of brushes may be selectively tripped during such return.

30. In a telephone exchange system, lines, a selector for seizing a line, said selector comprising a longitudinally movable shaft, a plurality of sets of brushes, resilient arms uniting said brushes to said shaft, means for laterally displacing the brushes of each set whereby said brushes are rendered inoperative, means for advancing said shaft a predetermined distance, means for retracting said shaft, and a tripping device whereby said brushes may be selectively released during such retraction.

40 31. In a telephone exchange system, lines, a selector for seizing a line, said selector comprising a support, a plurality of sets of brushes resiliently secured thereto, controlling means normally separating the brushes from each other to render the set inoperative, means for selectively advancing said support, means for returning said support, and a tripping device for selectively actuating by such return said controlling means to release a desired set of brushes.

45 32. In a telephone exchange system, conversational lines, a selector comprising an axially movable support, a plurality of sets of brushes secured thereto, a controlling means for each set normally holding the brushes thereof spaced to inoperative position, means for forwardly setting said support, means for retracting said support, and a tripping device whereby any desired brush set may be rendered active during such retraction.

55 33. An automatic switch comprising a movable shaft, a plurality of brushes resiliently secured thereto, controlling means individual to each brush for normally retaining said brushes in inoperative position, a

tripping device arranged to cooperate with each controlling means, means to successively actuate said tripping devices during the advance of said brush shaft, and means to release into operative position a desired one of said brushes by the joint action of a tripping device and a controlling means as a result of motion of said brush shaft.

34. An automatic switch comprising a movable shaft, a plurality of brushes resiliently secured thereto, controlling means individual to each brush for normally retaining said brushes in inoperative position, a tripping device arranged to cooperate with each controlling means, means to successively actuate and restore said tripping devices during the advance of said brush shaft, and means to release into operative position a desired one of said brushes by the joint action of a tripping device and a controlling means as a result of motion of said brush shaft.

35. An automatic switch comprising a movable shaft, a plurality of brushes resiliently secured thereto, controlling means individual to each brush for normally retaining said brushes in inoperative position, a tripping device arranged to cooperate with each controlling means, means to successively actuate said tripping devices during the advance of said brush shaft, and means to release into operative position a desired one of said brushes by the joint action of a tripping device and a controlling means as a result of longitudinal motion of said brush shaft.

36. An automatic switch comprising a movable shaft, a plurality of brushes resiliently secured thereto, controlling means individual to each brush for normally retaining said brushes in inoperative position, a tripping device arranged to cooperate with each controlling means, means to successively actuate said tripping devices during the advance of said brush shaft, and means to release into operative position a desired one of said brushes by the joint action of a tripping device and a controlling means as a result of a plurality of movements by said brush shaft.

37. An automatic switch comprising a movable shaft, a plurality of brushes resiliently secured thereto, controlling means individual to each brush for normally retaining said brushes in inoperative position, a tripping device arranged to cooperate with each controlling means, means to successively actuate said tripping devices during the advance of said brush shaft, and means to release into operative position a desired one of said brushes by the joint action of a tripping device and a controlling means as a result of a plurality of successive longitudinal movements by said brush shaft.

38. In a telephone exchange system, a

selector for seizing a line, said selector comprising a support, a plurality of sets of brushes resiliently secured thereto, a movable lever, a member secured to said support 5 arranged to move said lever from its normal position upon movement of said support, and controlling means normally separating the brushes of each set from each other to render the set inoperative, said controlling means 10 being positioned to engage said lever in a single one of its positions.

39. In an automatic switch, the combination with a rod, a plurality of brush sets secured thereto and a row of terminals, of

means for selectively adjusting said brush sets into operative position to engage said terminals comprising a plurality of brush tripping devices, one for each brush set, and cooperative means on said rod and tripping devices whereby the latter are successively 20 adjusted into tripping positions upon longitudinal movement of the rod, the particular brush set to be selected being determined by the stopping position of the rod.

In testimony whereof, I hereunto set my 25 hand.

GEORGE ALBEN E. LUNDELL.
